US0D1076512S

(12) United States Design Patent (10) Patent No.: US D1,076,512 S
(45) Date of Patent: * May 27, 2025

(54) QUILT COVER

(71) Applicant: JIANGSU E-BEST TEXTILE TECHNOLOGY CO., LTD., Nantong (CN)

(72) Inventor: Yang Wei, Nantong (CN)

(73) Assignee: JIANGSU E-BEST TEXTILE TECHNOLOGY CO., LTD., Nantong (CN)

() Term: 15 Years

(21) Appl. No.: 29/843,342

(22) Filed: Jun. 21, 2022

(30) Foreign Application Priority Data

Feb. 25, 2022 (CN) 202230093348.5

(51) LOC (15) Cl. 06-13

(52) U.S. Cl.

USPC D6/603

(57) CLAIM

The ornamental design for a quilt cover, as shown and described.

DESCRIPTION

FIG. 1 is a perspective view of a quilt cover showing my new design;

FIG. 2 is a front view thereof;

FIG. 3 is a rear view thereof;

FIG. 4 is a front view thereof showing the quilt cover in an open configuration; and,

FIG. 5 is a perspective view thereof in a folded configuration.

The broken lines shown in the drawings illustrate portions of the quilt cover that form no part of the claimed design.

1 Claim, 5 Drawing Sheets
